A. F. JACKSON.
BACK OF BRUSHES, MIRRORS, &c.

No. 20,430.

Patented Dec. 23, 1890.

UNITED STATES PATENT OFFICE.

AUSTIN F. JACKSON, OF TAUNTON, MASSACHUSETTS, ASSIGNOR TO THE
REED & BARTON CORPORATION, OF SAME PLACE.

DESIGN FOR BACK OF BRUSHES, MIRRORS, &c.

SPECIFICATION forming part of Design No. 20,430, dated December 23, 1890.

Application filed November 17, 1890. Serial No. 371,746. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Backs of Brushes, Mirrors, &c., of which the following is a specification, reference being had to the accompanying illustration, forming part thereof.

10 The figure is a photographic illustration of the back of a hair-brush or hand-mirror, showing my design.

My design for the back of a hair-brush or hand-mirror consists of a generally paddle-shaped contour with a scalloped border *a*, ornamented with inwardly-projecting scrolls and tongues. Within this border is another border *b* of oval shape and arabesque style of

ornamentation, and within the panel formed by this inner border is a picture of a young man reclining in an attitude of negligent ease against a rock, with a fair woman behind him in the act of blindfolding him or covering his head with a scarf. Upon the handle is emblazoned an irregular-shaped panel *c*. 20 25

The leading feature of my design is the central picture and the ornamental border inclosing the same, the handle portion being subordinate and non-essential.

What I claim is—

The design for the backs of brushes, hand-mirrors, &c., as herein shown and described.

AUSTIN F. JACKSON.
